UNITED STATES PATENT OFFICE.

CLARENCE DENNISON SWEET, OF CANASTOTA, NEW YORK, ASSIGNOR TO
THE CANASTOTA CASKET COMPANY, (LIMITED,) OF SAME PLACE.

DESIGN FOR A MEMORIAL ALBUM.

SPECIFICATION forming part of Design No. 19,648, dated February 11, 1890.

Application filed November 15, 1889. Serial No. 330,479. Term of patent 7 years.

To all whom it may concern:

Be it known that I, CLARENCE DENNISON SWEET, a citizen of the United States, residing at Canastota, in the county of Madison and State of New York, have invented and produced a new and original Design for Memorial Albums, of which the following is a specification, reference being had to the accompanying drawings, forming part thereof, in which—

Figure 1 is an isometrical elevation of a memorial album for coffin and casket plates showing my design, the album being closed. Fig. 2 is a top plan view of the same, the album being open.

The leading features of my design are a memorial album having in external outline the form of a book, and when open exhibiting a double frame having ornamental border-
20 panels.

A represents a memorial album simulating a book in external appearance, as shown in

Fig. 1, but when opened to exhibit the interior thereof, as shown in Fig. 2, will be seen to consist of two parts 1 and 2, similar to a back-gammon-ease. The parts 1 and 2 are provided with ornamental border-panels 3 and 4, respectively. Within the panel 3 is an ornamental border 5, and within the latter is a central panel 6, having a raised portion 7, formed with rounded edges 8 and corners 9, as shown.

Having thus described my invention, the following is what I claim as new therein and desire to secure by Design Letters Patent: 35

The design for a memorial album, substantially as herein described and shown.

In witness whereof I have hereunto set my hand this 11th day of November, 1889.

CLARENCE DENNISON SWEET.

In presence of—

D. T. WILLIS,
LEVI JAMES.
